DIAMOND DIE DRILLER

Fred Crossman, Earl A. Southam and George J. Ruhl, Cleveland, Ohio, assignors to The Lindsay Wire Weaving Company, Cleveland, Ohio, a corporation of Ohio

Application February 26, 1945, Serial No. 579,834

7 Claims. (Cl. 125—30)

1

This invention relates to apparatus for drilling relatively small holes in diamonds to form dies that are adapted to be used in processing wire. The holes to be drilled vary in size from four ten-thousandths of an inch to five thousandths of an inch in diameter.

Diamond die drilling machine having a vertically disposed drilling spindle have heretofore been used, but the machines have been somewhat complex in construction and have not only involved a problem of maintenance and repair, but also one of accuracy and selectivity in control of the moving parts. The drilling needle heretofore used has had a rotating and reciprocating motion imparted thereto, but the reciprocating motion has been uniformly regular in the time of contact with and withdrawal from the work. The purpose of the reciprocation is to afford an opportunity for the fluid-like abrasive material to enter the cavity in the diamond during the drilling operation, hence, it is desirable to be able to vary the period of contact and withdrawal of the needle from the work so as to impart a vibratory motion to the needle that is more effective in attaining the desired abrasive action than is possible with a uniformly regular period of contact and withdrawal.

In operating prior machines, as aforesaid, the needle must be frequently removed for dressing the point, and for such purpose considerable time has heretofore been lost in waiting for the needle to cease rotating under the influence of the momentum of the moving parts, and when it is considered that an operator is usually in charge of a battery of drilling machines, any time consumed in awaiting stoppage of rotation becomes an appreciable item in the course of a working day.

An object of the present invention is to make a diamond die drilling machine which is capable of drilling small holes having a diameter of the order heretofore set forth, and in accomplishing such purpose in a more satisfactory manner by reducing the working parts, by increasing the selectivity of control of the needle reciprocation, and by reducing the time required to change the needle whenever the need for dressing the point thereof becomes apparent. In this way, an operator may be in charge of a larger number of machines and the accuracy of the work may be greatly improved.

Referring now to the drawings, Fig. 1 is a side view partly in section of a machine embodying the present invention; Fig. 2 is a top plan view of the machine; Fig. 3 is a section taken on a plane indi-

2

cated by the line 3—3 in Fig. 1; Fig. 4 is a section taken on a plane indicated by the line 4—4 in Fig. 2; Fig. 5 is a section taken on a plane indicated by the line 5—5 in Fig. 4, and Fig. 6 is a vertical section taken through the needle driving mechanism.

We have shown our diamond drilling mechanism as being mounted upon a frame which includes a top frame plate 10 and a pair of horizontally disposed bearing plates 11 which are spaced from each other and are adapted to be held together in any suitable manner, as by the spacing members 12 and 13. The frame may support a plurality of drilling units but only one is illustrated in the drawings, it being understood that the construction of all are identical to that illustrated. Each drilling unit includes a rotatable work-supporting table 15 which may be supported by a vertically disposed shaft 16 that is journaled in bearings 17 in the respective bearing plates 11. The work table may have a smooth upper surface on which a work fixture 18 that carries the diamond to be drilled may be positioned and centered with respect to the needle.

10 The work table may be rotated by any suitable source of power through a driving belt 20 which extends around a driving pulley 21 that is fixed to the shaft 16 intermediate the bearings 17. In practice, the direction of drive is such that the work table rotates in a direction opposite to that of the drilling needle and at a slower speed.

15 25 The drilling mechanism is mounted on the upper frame plate 10 in such manner that the drill spindle and drill extend vertically. The mechanism includes a cylindrical frame or housing 25 which may be secured to the base plate 26 which rests upon the frame plate 10 and is adjustably secured thereto. Mounted within the housing are a pair of spaced vertically aligned bearings, preferably of the precision ball type, each of which has an inner race 27 and an outer race 28. The latter races engage in the inner wall of the housing and are secured thereto in the customary manner, while the inner races have rigidly secured thereto a sleeve 29 which has an axially extending passageway through which the needle holder is adapted to extend. The passageway through the sleeve, as shown in Fig. 6, has a clearance with the needle holder or spindle 30 except at the end portions thereof where a close sliding fit is provided by means of bushings 31 and 32 respectively.

20 25 30 35 40 45 50

The spindle 30 is preferably made of any suitable lightweight material and has its axis extending vertically. Moreover, the spindle has

such diameter that it will move freely in an axial direction through the bearings 31 and 32 under the influence of gravitation despite its lightness in weight. A needle 33 is mounted in a chuck 34 which is attached in any convenient manner to the lower end of the spindle.

By mounting the bearings adjacent the end of the housing 25 and by applying a driving rotational force intermediate the bearings, the spindle is not subjected to driving strains, wherefore frictional drag of the spindle in the bearing is eliminated, as well as any misalignment of the spindle that might be due to the drive. The driving connection may comprise a pin 35 which is shown as being rigidly carried by the sleeve adjacent the lower end thereof, and as being adapted to project into an axially extending slot 36 in the spindle 30. The slot is open at the lower end so that the spindle may be withdrawn whenever desired from the housing 25.

To rotate the sleeve 29, we have illustrated a belt 40 which is adapted to be driven by any suitable source of power (not shown) and which is arranged to extend around the sleeve and to engage a groove 41 therein for effecting a driving connection with the sleeve. In Fig. 6, the belt is shown in engagement with an idler pulley 42 which rotates freely on the sleeve 29. In such illustration, the sleeve is disconnected from the driving belt, but the change from the idler pulley to the driving groove 41 may be effected by means of a shipper lever 43 which may be pivoted at 44 to the housing, and may have a forked extension 45 which is adapted to engage one reach of the belt 40 and to shift it as desired.

To effect a rapid stopping of rotation of the sleeve 29 upon shifting of the belt onto the idler pulley, we utilize a braking mechanism in the form of a rod 46 which is slidably freely within a passageway in a housing 25 and which carries a shoe 47 at the inner end thereof for engagement with the sleeve.

Normally the shoe is held out of contact with the sleeve by a spring 48, one end of which bears against the housing and the other of which bears against the head 49 of the rod. Such head at the outer portion thereof is rounded for engagement by an arm 50 which is adapted to extend laterally of the lever 43. In the position shown in Fig. 6, the arm 50 is in engagement with the central portion of the head 49 at which time the spring is compressed and the shoe is in braking engagement with the sleeve 29. At the same time, the shipper lever 43 is in the position shown by the full lines in Fig. 1, and the belt 40 is thereby held on the idler pulley 42. When the shipper lever is moved to the broken line position 43A, however, the belt 40 is moved downwardly to the position 40A from the idler pulley 42 onto the sleeve groove 41, and the arm 50 is moved to the broken line position 50A, thereby allowing the spring 48 to release the brake so that a driving connection is made to the sleeve immediately upon shifting of the lever 43.

To effect a reciprocating action of the needle at selected intervals, we utilize a lever 55 which is pivoted at 56 to a block 57. The lever has a forked end 58 for engagement beneath a collar 59 on the spindle 30, and has the other end curved, as at 60, for engagement by cams 61 that are shown as being carried on the peripheral edge of a disc 62 that is fixed to a shaft 63. The shaft in turn is shown as being journaled in bearings 64 and 65, and as being driven by a belt 66 that extends around a pulley 67 that is shown as being

fixed to the shaft. The belt may be driven from any suitable source of power (not shown).

The cams 61 operate to effect intermittent rocking motion of the lever 55 about the pivot 56, and the position of the pivot is adjusted so as to impart a reciprocating action to the needle spindle, consequent upon contact of the various cams with the curved end 60 of the lever 55. The cams may be mounted at spaced intervals on the disc, suitable for any desired number of impulses to be imparted to the lever, per revolution of the disc 62. Thus, in the form shown, three impulses are made per revolution, with two of the cams being spaced 180° apart and the third cam being spaced 90° from the other cams. This arrangement will then give a dwell for one-half revolution of the disc and thereby allow sufficient time for the abrasive material to collect around the point of the needle.

To adjust the position of the pivot block 57, the block is illustrated as having a threaded passageway for engaging a threaded rod 68. The rod has a knob 69 at the end thereof and extends through an opening in a bar 70 that connects the tops of posts 71 which are illustrated as circular rods that act as guides for the block 57. For such purpose, opposing sides of the block are indented, as at 72 and 73, as is shown in Fig. 5. The spring 75 operates to urge the block 57 upwardly so as to hold a crosspin 76 on the rod 68 in engagement with the underside of the bracket 70. Thus, whenever the knob 69 is turned, the vertical position of the block 57 and, therefore, of the pivot 56, is adjusted with respect to a plate 77 that projects laterally from the housing 25 and carries the adjusting mechanism for the pivot 56, as well as the cam mechanism for operating the lever 55. Any adjustment vertically of the pivot alters the degree of reciprocation imparted to the needle spindle upon actuation thereof by contact between the cam 61 and the lever 55.

The drill spindle housing is arranged to be moved to align the drill with the work. To this end, the housing supporting plate 26 is slidably mounted upon the frame member 10 and the position of the mounting is adjustable by a pair of eccentric cams 80 and 81, while the table is secured in adjusted position by a clamping nut, indicated at 82.

The mechanism which we have illustrated will operate in a satisfactory manner to drill holes of relatively small diameter in diamonds with a high degree of precision. At the same time, it will permit selective control of the timing and extent of reciprocation of the needle during the drilling operation. The mechanism is simple and compact and lends itself to use in multiple arrangement, thereby enabling one operator to supervise the drilling of a large number of dies, and to stop the operation quickly on any particular die without necessitating a loss of time in adjusting the needle for dressing the point, or for replacing it with one of different size, as conditions may require.

We claim:

1. A machine for drilling comparatively small holes in work pieces, comprising in combination, a housing, spaced bearings carried by the housing, a sleeve interconnecting the bearings and having a belt groove thereon, an idler pulley journaled on the sleeve, a driving belt, means for shifting the belt between the pulley and sleeve groove, and a drill spindle extending through the sleeve and having a splined connection therewith, 75 whereby the spindle may be rotated but may be

withdrawn vertically from the machine without disturbing the driving connection therefor.

2. A machine for drilling comparatively small holes in work pieces, comprising in combination, a housing, spaced bearings carried by the housing, a sleeve interconnecting the bearings, a drill spindle extending through the sleeve and being freely slideable axially therein, said sleeve having a splined connection with the spindle whereby the spindle may be rotated but may be withdrawn vertically from the machine without disturbing the driving connection therefor, a driving belt extending around the sleeve intermediate said bearings, an idler pulley journalled on the sleeve, means for shifting the belt between the sleeve and pulley, and braking mechanism operable automatically with reference to the sleeve upon actuation of said means.

3. A machine for drilling comparatively small holes in work pieces, comprising in combination, a frame, spaced bearings carried by the frame, a sleeve journalled in said bearings, a drill spindle extending through the sleeve and being freely slideable axially therein, means for rotating the sleeve, said means including a belt adapted to be moved into driving engagement therewith, an idler pulley journalled on the sleeve and adapted also to receive said belt, said spindle having a splined driving connection with the sleeve so as to permit withdrawal of the spindle from the sleeve, a lever fitted to the housing and having belt-engaging means thereon for shifting the belt between the sleeve and idler pulley, and means actuated upon movement of the lever to engage the sleeve frictionally so as to arrest rotation thereof upon shifting of the belt from engagement with the sleeve onto the idler pulley.

4. A machine for drilling comparatively small holes in work pieces, comprising in combination, a frame, spaced bearings carried by the frame, a sleeve journalled in the bearings, a drill spindle mounted in said sleeve with its axis extending vertically, said spindle being freely slideable axially in said sleeve and having a detachable driving connection therewith, a belt for rotating the sleeve, a pulley wheel journalled on the sleeve, means for shifting the belt between the sleeve and wheel, the spindle having a collar thereon, a rockable lever adapted to engage the collar, a rotatable member having cam means thereon for engaging the lever at prearranged intervals, and means for shifting the position of the lever so as to vary the extent of movement of the collar-engaging portion thereof.

5. A machine for drilling comparatively small holes in work pieces, comprising in combination, a frame, spaced bearings carried by the frame, a sleeve journalled in the bearings, a drill spindle freely slideable axially in the sleeve and having a driving connection therewith whereby the spindle may be rotated but may be withdrawn vertically from the machine without disturbing the driving connection therefor, said sleeve having a peripheral groove therein, an idler pulley journalled on the sleeve adjacent said groove, a driving belt, means for shifting the belt between the groove and the pulley, a braking device movably mounted on the frame and adapted to engage the sleeve automatically upon actuation of the shifting means, means for imparting a reciprocating motion to the spindle during rotation thereof, said means including a lever pivoted in-

termidiate the ends thereof, said lever having one end thereof engaging the spindle, cam means adapted to engage the other end of the lever, and means for adjusting the position of the pivot vertically with respect to the spindle whereby the extent of axial movement of the spindle may be varied without varying the throw of the cam means.

6. A machine for drilling comparatively small holes in work pieces, comprising in combination, a frame, spaced bearings carried by the frame, a sleeve journalled in said bearings, a drill spindle mounted in the sleeve and being freely slideable axially therein, means for effecting a driving connection between the sleeve and spindle, whereby the spindle may be rotated but may be withdrawn vertically from the machine without disturbing the driving connection therefor, belt means for rotating the sleeve, an idler pulley associated with the sleeve and onto which the belt may be shifted, said idler pulley and belt being disposed between the bearings, a spring pressed plunger slidably mounted in the frame and having a brake shoe thereon adapted to engage the sleeve, means for shifting the position of the belt between the pulley and sleeve, a member for automatically actuating said plunger to effect a braking action on said sleeve consequent upon shifting of the belt from the sleeve onto the pulley, said spindle having a collar thereon, a lever having a forked end for receiving the spindle and engaging the collar, said lever having a pivot intermediate the ends thereof, means for shifting the position of the lever vertically with respect to the frame, and means adapted to engage the other end of said lever, said means including a rotatable disc, and cam members mounted at spaced intervals thereon.

7. A machine for drilling comparatively small holes in work pieces comprising in combination, a frame, spaced bearings carried by the frame, a sleeve journalled in said bearings, a drill spindle extending through said sleeve and being freely slideable axially therein, means disposed intermediate the bearings for rotating the sleeve, means for effecting a driving connection between the sleeve and spindle, and means for reciprocating the spindle during the rotation thereof, said means including a rockable lever pivoted intermediate the ends thereof, means for shifting the pivot vertically with respect to the frame, said lever having one end thereof engaging the spindle, and cam means engaging the other end of the lever, said cam means comprising a rotatable disc having protuberances disposed at spaced intervals on the periphery thereof.
